United States Patent Office.

A. VAN GUYSLING, OF WEST ALBANY, NEW YORK.

Letters Patent No. 96,746, dated November 9, 1869.

IMPROVEMENT IN MECHANICAL MOVEMENTS.

The Schedule referred to in these Letters Patent and making part of the same.

To all whom it may concern:

Be it known that I, A. VAN GUYSLING, of West Albany, in the county of Albany, and State of New York, have invented certain new and useful Improvements in Mechanical Movements; and I do hereby declare that the following is a full, clear, and exact description thereof, reference being had to the accompanying drawings, and to the letters of reference marked thereon, which form a part of this specification.

The nature of my invention consists in the construction and arrangement of certain devices, by which an oscillating motion is converted into a rotary motion, and also in the manner of rotating a spindle or shaft, in either direction, by applying a single or double spring.

In order to enable others skilled in the art to which my invention appertains, to make and use the same, I will now proceed to describe its construction and operation, referring to the annexed drawings, in which—

Figure 1 is an end view, and

Figure 2, a plan view of my invention.

Figure 3 is a side view of the oscillating lever, with the springs attached.

Figure 4 is a side view of the spindle or shaft, and

Figure 5 is a perspective view of the connecting-piece between the oscillating lever and the spindle or shaft to which it is desired to contribute a rotary motion.

A represents the rod or lever, which, by any machinery or device, has an oscillating motion.

Its inner end is slightly bevelled outward, from the centre to the upper and lower edges, as seen in fig. 3, forming a depression across the centre.

This end of the lever A is also slotted, and in this slot is pivoted a three-cornered block, a, from the base of which project two curved springs, b b, one above and one below the bevelled end of the lever.

The outer angle or corner of the block a is slightly raised upward, or pressed downward, by means of a pin, e, which is inserted either below or above said block, through the lever A, as seen in figs. 2 and 3.

The bevelled end of the lever A is inserted into a recess, d, in an elliptical-shaped block or cylinder, D, and pivoted in the same, said recess opening into a round hole, f, through the block, running at right angles with the lever A.

The edges of the bevelled end of the lever A project slightly within the hole f, when the lever is either raised or lowered, but when held in a certain position, the edges should be even with the sides of the hole f.

The springs b b, when the lever A is pivoted in the recess d, bear on the outside of the cylinder, one above and the other below the same.

Through the hole f, in the cylinder D, is placed a spindle or shaft, B, which, at the point where the recess d opens into the hole f, is not round, but polygonal-shaped, as shown in fig. 4.

It will readily be seen, that when the pin e is inserted, either above or below the block a, the lever A, by the action of the springs b b, on the outside of the cylinder D, becomes rigidly fixed in said cylinder, in such a manner that one of the edges will project from the recess d, and bear against the sides of the shaft B, and consequently, when the lever A is in motion, that is, has its oscillating motion, it will turn the shaft during, for instance, its upward motion, but slip over the same during its downward motion, and thus cause the shaft to turn steady in one direction.

The direction in which the shaft B turns is easily changed, by moving the pin e to the other side of the block a, as that at once changes the position of the edges of the lever within the recess a, the springs b b at all times holding the lever rigid enough to turn the shaft, but still yielding a trifle at the first shock.

By these means, the oscillating motion is converted into rotary motion, and the direction of the rotary motion is changed by the springs holding the oscillating lever in the required position.

Having thus fully described my invention,

What I claim as new, and desire to secure by Letters Patent, is—

1. The oscillating lever A, constructed as described, with bevelled end, and a slot through the same, substantially as and for the purposes herein set forth.

2. The three-cornered block a, provided with springs b b, substantially as and for the purposes herein set forth.

3. The combination of the lever A, block a, springs b b, pin e, and cylinder D, all constructed as described, and for the purposes set forth.

4. The combination and arrangement of the oscillating lever A, with the block a, springs b b, and pin e, the cylinder D, and shaft B, all constructed as described, and operating substantially in the manner and for the purposes herein set forth.

In testimony that I claim the foregoing, as my own, I affix my signature, in presence of two witnesses.

A. VAN GUYSLING.
